RAY H. MANSON, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

HOOKSWITCH AND CIRCUITS THEREFOR.

1,303,351.

Specification of Letters Patent.

Patented May 13, 1919.

Application filed December 18, 1916. Serial No. 137,620.

To all whom it may concern:

Be it known that I, RAY H. MANSON, a citizen of the United States, residing at Rochester, in the county of Monroe and 5 State of New York, have invented certain new and useful Improvements in Hookswitches and Circuits Therefor, of which the following is a complete, clear, and exact description.

10 It has been customary in improved telephone systems to arrange the sub-station apparatus with circuit connections so as to secure the maximum of telephonic transmission when the subscriber speaks into his telephone transmitter.

15 These circuit connections, however, while producing the above desired results, produce an undesirable result in that the "side-tone" effect is increased; that is, there is re- 20 produced in the telephone receiver of the transmitting sub-station to an abnormal degree, the sounds which are projected into the transmitter of that station, the receiver reproducing these sounds to such an abnormal 25 degree that the various noises of the room in which the telephone instrument is placed will be heard and will drown out much of the sound in the receiver, due to the incoming voice currents from the distant station.

30 Circuits have also been proposed which will not have this excessive "side-tone" effect in the receiver but these circuits are invariably attended by a loss in outgoing transmission.

It is particularly the object of this invention to produce a switchhook combination 35 which will permit the use of either type of circuit at the will of the sub-station instrument user, whereby such user can obtain the use of a telephonic circuit of high transmitting power, or when this is not required, can obtain the use of a circuit in which the "side-tone" is not so severe, for ordinary local 40 conversations.

Another object of my invention is to provide an improved means for accomplishing the different switchhook positions whereby 45 different circuit connections are caused, so that the same shall be positive in action, have a pleasing appearance to the eye, at the

same time being of durable construction so 50 that it cannot be injured by abuse or by a long continued use.

Other objects of my invention and the invention itself will be apparent from the accompanying description of the embodiment 55 illustrated in the drawings.

I have shown an embodiment of my invention in the accompanying drawings, in which similar reference characters have been used in the different figures to designate like 60 parts.

Figure 1 shows partly in cross-section and partly in side elevation a switchhook structure of an embodiment constructed in accordance with my invention.

Fig. 2—N shows an end view of the latch of the switchhook in its normal or unoperated position but illustrated as broken away so as to show the latch mechanism.

Fig. 2—O likewise shows the switchhook 70 latch in the intermediate or latched position and Fig. 2—P likewise shows the switchhook latch in its released or ultimate position.

At 2—A and 2—D I show normal circuit 75 connections of two forms of my invention at the time the switchhook and latch therefore is in normal position, as shown in Fig. 2—N.

At 3—B and 3—E I show the circuit connections of the two forms of my invention 80 illustrated in Figs. 2—A and 2—D, in the intermediate or latched position of the switchhook as illustrated in Fig. 2—O.

At 4—C and 4—F I show the circuit connections of the two forms of my invention 85 illustrated, in the fully operated or released position of the switchhook mechanism illustrated in Fig. 2—P.

Figs. 2—A, 3—B and 4—C illustrate circuit connections for the use of my invention 90 in connection with circuits involving the use of what is known as a direct current receiver; that is, such a receiver as is operated with the direct line current passing through its winding.

At Figs. 2—D, 3—E and 4—F I illustrate the use of my invention in connection with telephone circuits involving the use of

the ordinary magneto receiver which operates without the direct battery current from the line passing through its winding.

Fig. 1 shows a side elevation of the parts 5 of the switchhook mechanism inclosed inside the telephone casing; it also shows in cross-section the parts of the switchhook mechanism not inclosed inside the telephone casing and comprise a portion of a side of 10 the telephone casing and the external parts, such as the latch L, etc.

The internal parts comprise a frame f, whereon the switchhook lever H is pivoted at p, the switchhook carries an insulated 15 roller r, contacting normally with a lever switch spring 1. This lever switch spring is adapted to be moved by the roller r, and to cause the set of switch springs s to be operated.

20 A portion of a side of the telephone casing is illustrated at G, an escutcheon plate being mounted on the outside thereof, shown at e, and is secured through the walls of 25 the casing to the frame f, by means of machine screws m₁ and m₂. The machine screw m has a flanged bushing-washer b secured firmly between the head of the screw m and the escutcheon plate e. Pivoted loosely between the flanges of this bushing-washer and 30 adapted to rotate on the same is the latch member L. These external parts, including the latch member, are perhaps more clearly understood by reference to the views at 2-N, 2-O and 2-P which shows a side 35 view of these parts in the different operating positions.

Referring to these latter figures, I provide an inclined cam surface c for the latch which is engaged by the hook H. This construction involving such a cam surface is important, as by means of this and the provided construction of the coöperating parts, I am enabled to forcibly return the latch member L to normal position as illustrated 40 at 2-N from the ultimate position as illustrated at 2-P by means of the forcible propelling of the same by means of the under surface of the switchhook lever H engaging this cam surface. I thus do not depend 45 upon the force of gravity alone as in prior constructions of such devices with which I am familiar, wherein dependence is placed upon the gravity force overcoming the friction between the mobile part or parts and 50 the stationary parts to which they are secured.

Furthermore, I do not clamp, as in prior 55 constructions, the latch member L directly to the casing or escutcheon plate by means of the machine screw m but provide a non-corrosive flanged metal bushing b upon which the latch member is pivoted loosely, the flanges preventing the screw from binding the latch member L as would otherwise

occur and as does often occur in prior constructions above referred to.

Referring now to Figs. 2-A and 2-N these show the latch member, the switchhook and the circuit connections in normal or un-operated position. In Fig. 2-A I show the 70 receiver 5 resting upon the switchhook H thereby causing contacts between the springs 1 and 2 to be made. The connection between the springs 1 and 3 will be broken, thereby causing the circuit connections between the line wires 7 and 8 to be discontinuous which will cause the signal apparatus, not shown, at the Central Office to indicate the non-busy condition of the line.

Now, if the subscriber desires to place the 80 apparatus in conversational circuit with the central office equipment the receiver 5 will be removed from the switchhook lever H causing the lever H to take the position indicated in Fig. 2-O, the latch member L, 85 by its latching tongue 9, preventing the lever from rising any further at this time. The conversational circuit between the line wires 7 and 8 is now closed, the circuit causing this closing being traced as follows: 90 From line wire 7 through the transmitter 10, contacts springs 3, 1 and 2, conductors 11 and 12, receiver 5, to the other line wire at 8. It will thus be seen that the primary winding 13 of the induction coil 14 is not 95 in circuit and the secondary winding 15 of the induction coil is short-circuited and thus disabled by the closure of the contacts of the springs 1 and 2.

The circuit then briefly consists of the 100 conducting wires, the transmitter and the receiver in serial circuit with the line wires. This provides a circuit in which the transmission is not as efficient as that which will later be described but in which the "sidetone" effect is minimized producing an agreeable effect to the telephone user who presumably, when using this circuit, does not need the highest degree of transmission efficiency but is possibly using the line to 110 converse with nearby stations in which such high degree of transmission is unnecessary. Such conversational circuits wherein the stations are not far apart, exceed in number, those in which the stations are far distant 115 from each other and therefore, in a majority of cases, the circuit connections, as shown in Fig. 3-B and with the latch member in the position shown at 2-O will be used.

For long distance connections, however, where the parties are apart a distance one from the other, a more efficient sub-station transmitting circuit is highly desirable. Such a circuit can be readily obtained by 125 operating, manually, the latch member L, so that the switchhook lever H advances to its ultimate or extreme operating position

and the latch taking the ultimate position as shown in Fig. 2—P. The circuits will then be as shown in Fig. 4—C which shows the springs 1, 3 and 4 through their contacts 5 making electrical connection one with the other, and breaking the circuit between the contacts of springs 1 and 2. Thus the short circuit is removed from the secondary winding 15 of the induction coil 14, and the primary winding 13 is connected in conversational circuit in series with the condenser 16, across transmitter 10. Under this condition the well known "Booster" sub station circuit is formed in which as is well known 10 the outgoing transmission is quite powerful, this circuit being well known in the art, and it is not necessary to describe the same in detail. In this use of the "Booster" circuit the direct current receiver 5, is connected serially in the line wire 8.

Figs. 2—D, 3—E and 4—F show an embodiment of my invention wherein a magneto type receiver is used, and it is, therefore, not connected serially in the line as in 15 the circuits just described, but is connected in series with the condenser 16, and the primary winding 13 of the induction coil 14. Fig. 2—D shows the circuit connection with the receiver 5 on the hook, and the circuit 20 connection between the line wires 7 and 8 being disconnected on account of the open contacts of the switch springs 17, 18 and 19. When the circuit is taken for use the subscriber removes the receiver 5 from the 25 switchhook, and with the latch and hook members in the position shown in Fig. 2—O, the circuit connections are as illustrated in Fig. 3—E. The switch springs 19 and 20 are un-operated, and through their contacts 30 remain in connection one with the other. The switch springs 17 and 18 make connection through their contacts at this time, completing the circuit for the transmitter 10, between the line wires 7 and 8.

The circuit then briefly consists of a conducting wire leading from line wire 7 from the transmitter 10 through switchhook contacts of the springs 17 and 18, the winding 15 of the induction coil 14, which winding 35 in this case is a primary winding, to the other line wire 8. The receiver 5 is connected in a local circuit consisting of a winding 13 of the induction coil, which winding in this case is a secondary winding, 40 the condenser 16, the conducting wire 21, the switch spring 20, the switch spring 19, and the conducting wire leading back to the receiver 5. Thus, the circuit with the hookswitch latched as in Fig. 2—O is that of an 45 induction coil circuit well known in art, having a local receiving circuit, and while fairly efficient for receiving, is not so efficient for outgoing transmission. The "side-tone" effect is less than in the form to be

described which has a high efficiency for 65 outgoing transmission as will later be discussed. The circuit just described, would just as in the case of the circuit shown in Fig. 3—B have a considerable use for local 70 conversational telephone circuits wherein powerful transmission is not an object, but wherein the "side-tone" effect is especially undesirable.

Now, should the subscriber desire to obtain the use of a circuit possessing the highest 75 degree of outgoing transmission efficiency as for long distance connections, he will depress, manually, the latch member L to the position shown in 2—P, allowing as shown in this figure the hookswitch lever H 80 to advance to its highest or ultimate position. Under this condition the circuit connections illustrated in Fig. 4—F form the well known "Booster" circuit, and which is briefly described as follows:—In this circuit the winding 15 becomes a secondary winding, and the winding 13 primary winding 85 of the induction coil 14.

The contacts of the springs 17, 18 and 19 making electrical connections one with the other cause the conversational circuits to be closed through these contacts. The receiver 5 is now shown serially connected with the condenser 16, and the primary winding 13 across the transmitter 10. When the subscriber speaks into the transmitter, the transmitter varying its resistance will vary the potential at its terminals and thereby vary the charge of the condenser 16, as well 90 varying the line current directly. This effect causes a varying current to flow through the primary winding 13, which is reproduced in the winding 15 in the well known manner augmenting the effect of the varying current in the line above mentioned. 95 This produces very powerful undulations of currents in the line wires causing the well known so-called "Booster" effect on outgoing transmission, but at the same time creating a very considerable undulating or 100 varying current to flow through the receiver 5, producing a considerable "side-tone" effect in this receiver. For this reason this powerful transmission circuit would only 105 be used for long distance connections, and would not be used in the majority of connections.

I have above described the various illustrated hook and latch positions and the circuits resulting therefrom, from the normal 120 position to the ultimate position of the switchhook and latch. When the subscriber finishes the telephonic conversation, he will replace his receiver upon the hookswitch lever and cause it to descend. The bottom 125 of the lever during its downward movement will come into an engagement with the cam surface c of the latch member, forcing the

latch member forward, and its face portion downward until it is restored to its normal position as shown in Fig. 2—N, from the ultimate position as shown in Fig. 2—P.

5 I am aware that numerous and extensive departures can be made from the embodiments shown herein and described above, such embodiments being illustrated so that my invention can be more clearly understood, and not for the purpose of limiting the same.

What I claim is:—

1. In a telephone substation, telephone elements therefor, a plurality of circuits 15 for said elements, one of said circuits being adaptable to produce high efficiency telephonic transmission, another circuit being adaptable to produce a less efficient telephonic transmission, switch springs adapted 20 by their movement to switch the telephone elements to either of said circuits, a lever member for said switch springs, a latch for said lever member, said latch controlling the position of said lever to cause the lever 25 member to operate the switch springs to make proper connections for either of said circuits.

2. In a switchhook circuit, a switchhook, a lever member therefor having a plurality 30 of operative positions and a normal position, switch springs operated by said lever to make different electrical connections at each operative position said switch springs disengaged when in normal position, a latch to 35 retain said switch lever in one of said operative positions, manually operated means integral with said latch to cause said lever to take a second operative position, a relatively low efficiency telephone circuit, a 40 relatively high efficiency telephone circuit, said low efficiency circuit being formed by said first connections and said high efficiency circuit being formed by second connections.

3. In a telephone, a switchhook therefor, 45 a booster circuit therefor, an anti-side tone circuit therefor, an automatically operated lever for said switchhook to connect said booster circuit to the line wires of said telephone, or to connect said anti-side tone 50 circuit to said line wires, said lever automatically operated to connect said anti-side tone circuit, and manually operated to connect said booster circuit.

4. In a telephone substation instrument, a 55 telephone receiver therefor, supporting means for the said telephone receiver,

spring means to move the said supporting means when the said receiver is removed from the said supporting means, a plurality of sets of electrical contacts, means to cause one of the said sets of contacts to be operated by the moving of the said supporting means to connect in conversational circuit the transmission elements of the said telephone according to a given manner of connections for outgoing and incoming telephonic transmission, stop means to stop the said support in the said movement at a point where it fails to operate the second set of contacts, the said stop means being capable of manual operation to cause the said supporting means to continue its movement to a position wherein the second set of contacts are operated, the operation of the second set of contacts changing the manner of 75 connection of the transmission elements of the said telephone to produce a different operative transmission effect for incoming and outgoing transmission.

5. In a telephone substation instrument, a 80 telephone receiver therefor, a telephone transmitter therefor, an induction coil and condenser with circuit conductors connecting the said receiver, transmitter, induction coil and condenser to connect the same in a 85 given manner to produce a given effect for incoming and outgoing telephonic transmission, supporting means for the said telephone receiver, motor means to move the said supporting means when the said receiver is removed from the said supporting means, a plurality of sets of electrical contacts in the said circuit conductors, means to cause one of the said sets of contacts to be operated by the moving of the said supporting means to connect in conversational circuit the transmission elements of the said telephone according to the above manner of connections, and manually operated means to extend the movement of the said supporting means to cause the said second set of electrical contacts to be operated, the operation of the second set of contacts altering the circuit connections between the telephone elements to produce a different operative 105 transmission effect between the said transmitter and the said receiver, and for incoming and outgoing transmission.

In witness whereof, I hereunto subscribe my name this 16th day of November, A. D. 110 1916.

RAY H. MANSON.
